TORCH

Warren A. Sparks, Long Beach, Calif., assignor to
John M. Henry, Los Angeles, Calif.

Application January 28, 1950, Serial No. 140,981

2 Claims. (Cl. 158—27.4)

1

This invention relates to torches, and more particularly to oxyacetylene torches of the trigger type.

While there have been proposed various acetylene torches operated upon the snap of a trigger to strike a striker against the flint to light the acetylene flame, it is believed that heretofore no one has successfully proposed such a trigger operation built into the torch for oxyacetylene use. In the use of an oxyacetylene torch, however, it is necessary to first ignite the pure acetylene flame and thereafter to supply to the acetylene flame the oxygen supply, and accordingly, it is a feature of this invention that upon initial actuation of the trigger mechanism, the supply of acetylene is turned on and thereafter the strike of the flint is made, but prior to the opening of the passage for the supply of oxygen, thus assuring that the acetylene flame is ignited prior to supplying oxygen thereto.

It is, accordingly, one object of this invention to provide an oxyacetylene torch having a trigger action for igniting the flame.

It is a further object of this invention to provide such an oxyacetylene torch in which means is provided for first turning on the supply of acetylene, secondly igniting the acetylene flame, and lastly turning on the supply of oxygen.

In achieving these objects, novel valve means hereinafter described have been invented and it is, accordingly, one object of this invention to provide such novel valve means capable of sequentially supplying initial flow of acetylene and then oxygen and thereafter concurrently supplying acetylene and oxygen to the torch.

These and other objects and advantages of the invention will be apparent from the annexed specification in which:

Figure 1 is a vertical section through a torch embodying the present invention;

Figure 2 is a left side view of the device shown in Figure 1;

Figure 3 is a section taken along the line 3—3 of Figure 1; and

Figure 4 is a section taken along the line 4—4 of Figure 1.

Referring now more particularly to the drawings, the numeral 10 indicates a body member which, as shown particularly in Figure 3, is channel shaped in cross section, having legs 11 and 12. The lower edges of the legs 11 and 12 are curved as at 13 to provide a hand grip and between the two legs there is pivotally mounted a trigger member 14 mounted upon a pin 15. The trigger member 14 is, itself, preferably channel shaped, as shown in Figure 3, and has a corresponding rounded lower surface 16 for ease of gripping by the hand of the operator. The body portion 10 has a web 17 which is bored throughout its length as at 18. Intermediate its ends, the web portion 17 has its lower half cut away, forming an opening 19.

The body portion 10, toward the left hand side is enlarged to form a circular member 20. The circular member 20 is shown as provided with a hub 21 on one side, and a hub 22 on the other side.

The circular member 20 is provided with a pair of bores 23 and 24, and is tapped at 25 and 26 to receive the members 27 and 28 to which the acetylene and oxygen supply tubes, respectively, are attached. Transversely the circular member 20 is bored and tapped to receive the needle valves 29 and 30 which regulate the rate of supply of acetylene and oxygen, respectively. O-rings 31 are provided for sealing the needle valves. The bore 24 is aligned with and communicates with the bore 18 in the web 17. The bore 23 traverses the hubs 21 and 22 and on its right hand side is tapped as at 32 to receive a tube 33 which communicates with the bore 23 and is itself affixed in an opening 34 in the web 17. The bore 18 at its farthest left hand extremity is tapped as at 35 to receive the threads of a short length of tubing 36 which is positioned within the bore as shown in Figure 1. A further tube 37 having an enlarged boss or ring 38 disposed centrally thereon is disposed in the bore 18 with a portion extending into the tube 36, as shown in Figure 1. To the right of the tube 37, a further tube 39 is disposed within the bore 18 and a portion of the tube 37 extends into the tube 39, and the left hand side of the tube 39 engages the boss 38, as shown. The tube 39 is bored as at 40 to receive the inner end of the tube 33 and thus acetylene from the member 27, the bore 23 and the tube 33 is passed to the interior of the tube 39. To the right of the tube 39, a tube 41 is located in the bore 18. A piston 42 is provided having one end extending into the tube 41 to the left of the opening 19 and the other end extending into a tube 43 to the right of the opening 19. The tube 43 is located in the bore 18, as shown in Figure 1. Piston 42 has an enlarged portion or collar 44 located in the opening 19. The piston 42 is itself provided with a central bore 45 and a pair of sealing O-rings 46 and 47 are provided in grooves in the piston to seal the same to the tubes 41 and 43, respectively. A transverse bore 48 is provided toward the left end of the piston

42 communicating with the central bore 45. The web 17 terminates at 50 and a tube 51 provided with a reduced end 52 is positioned beyond this termination with the reduced end 52 received within the tube 43 and sealed thereto by an O-ring 53. At its right end, the tube 51 is tapped as at 54 to receive the burner tube 55. The burner tube 55 is supported at 54 and in rounded portions 56 and 57 in the upper walls of the legs 11 and 12, as shown in Figure 4. The tube 51 has a central bore 58 communicating the interior of the tube 43 and the interior of the burner tube 55. The tube 55 is bored as at 60 to provide a spark opening.

A shaft or pin 61 is journaled in the legs 11 and 12 and carries a pinion 62 and a striker or steel 63. A second pin 64 is mounted in the walls 11 and 12 and slidably supports a rack 65. The rack 65 is carried by a rod 66 which is provided with a pin 67 for retaining a coil spring 68 mounted thereon. A pin 69 extends across the two legs of the channel shaped trigger 16 and carries a peg 70 which peg 70 is adapted to support the left end of the coil spring 68. The peg 70 is terminated short of the left end of the rod 66 to normally leave a clearance between the two, as shown in Figure 1.

A tube 80 is mounted between the two sides or legs 11 and 12 and receives a rod or post 81. The rod or post 81 is integral with a cross member 82 which also carries a further rod 83 and a thumb knob 84. The rod 83 has affixed to its left hand end one end of a coil spring 85, the other end of which is affixed to a pin 86 carried by the two arms of the channel shaped trigger member 16, as shown in Figure 3. A piston-like flint member 90 is positioned within the tube 81 and adapted to be engaged by the striker wheel 63.

A pin 91 is mounted between the two legs 11 and 12 and pivotally mounts a bell crank or lever 92 having one leg engaging the collar 44 and the other leg engaging the upper periphery 93 of the trigger 16.

The operation of the above described device is as follows:

Assuming that oxygen and acetylene tubes have been attached to the members 28 and 27, respectively, and it is desired to operate the torch, the operator merely seizes the same in one hand with his fingers wrapped about the trigger 16. Depressing the trigger 16 causes the same to pivot about the pivot point 15 and to compress the coil spring 68. After the coil spring 68 has been compressed sufficiently to overcome the resistance of the flint against the striker wheel 63 caused by the coil spring 85, the rod 66 and consequently the rack 65 will be forcibly moved to the right with a snap action. Coincidentally, the pinion 62 and the striker wheel will be revolved, the striker wheel 63 throwing a spark from the flint 90 through the bore 60 into the combustion tube 55. Sufficient air is admitted into the combustion tube 55 through the opening 60 to promote ignition.

While the above described operations are being carried out, the bell crank or lever 92 has been engaged by the trigger and pivoted in a counter-clockwise direction, thus moving the piston 42 to the left. The left end of the piston 42 engages a rod 100. The rod 100 is positioned within an enlarged bore 101 in a tube 102. Tube 102 is provided with a collar 103 received between the tubes 39 and 41. The rod 100 toward its left end is provided with an enlarged head 104 to the right of which there is applied a rubber sealing ring

105 adapted to seat against the left end of the tube 102. The rod 100 has an extension 106 upon which is mounted one end of a coil spring 107 which coil spring is mounted within the tube 39. Movement of the piston 42 to the left causes the same to force the rod 100 to the left, thus unsealing the sealing ring 105 from the tube 102. The enlarged head 104 and the sealing ring 105 are of lesser external diameter than the interior diameter of the tube 39 and thus acetylene supplied to the interior of the tube 39 by the tube 33 is permitted to enter the clearance within the bore 101 and hence through the transverse bore 48 to the bore 45 of the piston. From the bore 45, the acetylene passes through the bore 58 into the interior of the tube 55.

A second rod 110 similar to the rod 100 is provided, located mostly within the tube 37 but having one end extending beyond the tube 37 to receive the other end of the coil spring 107. The rod 110 is likewise provided with an enlarged head 111 and a sealing ring 112 adapted to engage the left end of the tube 37 and seal the same. A coil spring 113 is provided in the tube 36 having one end abutting the enlarged portion 26 and the other end abutting the enlarged head 111.

Further movement of the piston 42 to the left will cause the left end of the rod 100 to engage the right end of the rod 110 and move the same to the left, thus unseating the sealing ring 112 from the tube 37 and permitting oxygen to pass through the member 28 to the bore 24, the tubes 36 and 37 and to the interior of the tube 39. Thus, it will be noted that the sequence of operations is first the opening of a supply of acetylene to the burner tube, second a movement of the striker against the flint to ignite the acetylene, and lastly an opening of the supply of oxygen to the burner tube for the creation of an oxygen acetylene flame. If it is desired to extinguish the flame, a mere release of the trigger 16 will cause the piston 42 to move to the right under the force of the coil springs 85 and 113, and thus close the passages for the supply of acetylene and oxygen.

If the flint 90 becomes worn out, it is only necessary for the operator to seize the thumb knob 84 and pull the same to the right against the force of the spring 85 until the rod 81 is removed from the tube 80, at which time a new flint can be inserted therein and the device reassembled.

While there has been described what at present is considered a preferred embodiment of the present invention, it will be apparent to those skilled in the art that various changes and modifications can be made therein without departing from the essence of the invention and it is intended to cover herein all such changes and modifications that come within the true spirit and scope of the appended claims.

60 What is claimed is:

1. A torch comprising: a body; a burner tube; a trigger; a flint and striker; resilient means biasing said flint against said striker; resilient means connecting said trigger and said striker and operable to snap said striker against said flint on compression sufficient to overcome the resistance of said flint against said striker to ignite gas in said burner tube; said body having a longitudinal bore; a piston slidably in said bore and operably associated with said trigger; said piston being provided with a longitudinal gas passage; a conduit for supplying acetylene to said bore; a valve seat in said bore; a valve associated with said valve seat and having a stem;

said stem being engageable by said piston upon actuation of said trigger to unseat said valve; a spring normally biasing said valve against said seat; a second valve seat in said bore having an opening communicating with said first valve seat; a second valve associated with said second valve seat and having a stem engageable upon further movement of said piston by said first valve to unseat said second valve; a second spring normally biasing said second valve toward closed position; a conduit for supplying oxygen to said bore on the inlet side of said second valve, whereby on actuation of said trigger said first valve is opened to first admit acetylene to said burner tube, said flint is next sparked to ignite said acetylene and said second valve is then opened to admit oxygen to said burner tube.

2. A torch comprising: a body; a burner tube; a trigger; a flint and striker; resilient means biasing said flint against said striker; resilient means connecting said trigger and said striker and operable to snap said striker against said flint on compression sufficient to overcome the resistance of said flint against said striker to ignite gas in said burner tube; said body having a longitudinal bore; a piston slideable in said bore and operably associated with said trigger; said piston being provided with a longitudinal gas passage; a conduit for supplying acetylene to said bore; a valve seat in said bore; a valve associated with said valve seat and having a stem; said stem being engageable by said piston upon actuation of said trigger to unseat said valve; a spring normally biasing said valve against said

seat; a second valve seat in said bore having an opening communicating with said first valve seat; a second valve associated with said second valve seat and having a stem engageable upon further movement of said piston by said first valve to unseat said second valve; a second spring normally biasing said second valve toward closed position; a conduit for supplying oxygen to said bore on the inlet side of said second valve, whereby on actuation of said trigger said first valve is opened to first admit acetylene to said burner tube, said flint is next sparked to ignite said acetylene and said second valve is then opened to admit oxygen to said burner tube; and auxiliary valve means for regulating the proportions of oxygen and acetylene thus supplied to said burner tube.
